UNITED STATES PATENT OFFICE.

A BRAHAM SYDEMAN, OF BOSTON, MASSACHUSETTS.

DESIGN FOR A HEEL FOR BOOTS OR SHOES.

SPECIFICATION forming part of Design No. 30,926, dated May 30, 1899.

Application filed May 1, 1899. Serial No. 715,248. Term of patent 7 years.

To all whom it may concern:

Be it known that I, ABRAHAM SYDEMAN, a citizen of the United States, residing at Boston, in the county of Suffolk and Commonwealth of Massachusetts, have invented and produced a new and original Design for a Heel for a Boot or Shoe, of which the following is a specification.

The drawing shows in perspective a heel for a boot or shoe, illustrating my design.

The leading feature of my design for a heel for a boot or shoe consists in a body having a rib or projection on its tread-face extended adjacent the perimeter thereof.

The body a , having a breast portion a' , is provided on its tread-face with a rather broad flat rib or projection a^2 , adjacent the perim-

eter of the body, the depression a^3 , bounded by the rib, having a plurality of separated projections a^4 therein.

My design for a heel is also applicable for a top lift.

Having fully described my invention, what I claim, and desire to secure by Letters Patent, is—

The design for a heel for a boot or shoe, substantially as herein shown and described.

In testimony whereof I have signed my name to this specification in the presence of two subscribing witnesses.

ABRAHAM SYDEMAN.

Witnesses:

JOHN C. EDWARDS,
AUGUSTA E. DEAN.
